UNITED STATES PATENT OFFICE.

MARIE ANTOINETTE HEES, OF ST. JOSEPH, MISSOURI.

DESIGN FOR A CROCHET LACE DRAPING.

46,732.

Specification for Design.

Patented Dec. 8, 1914.

Application filed September 24, 1914. Serial No. 863,414. Term of patent 3½ years.

To all whom it may concern:

Be it known that I, MARIE ANTOINETTE HEES, a citizen of the United States, residing at St. Joseph, in the county of Buchanan and the State of Missouri, have invented a new, original, and ornamental Design for Crochet Lace Drapings, of which the following is a specification, reference being had to the accompanying drawing, forming part thereof.

The figure is a plan view of a crochet lace draping, showing my new design.

I claim:

The ornamental design for a crochet lace draping, as shown.

MARIE ANTOINETTE HEES.

Witnesses:

E. F. HARTZELL,
MARIE C. HECKEL.
